Application February 15, 1936, Serial No. 64,028

14 Claims. (Cl. 250—36)

This invention relates to high-frequency signaling apparatus and more particularly to improvements in regenerative circuits of the type conventionally employed in electron discharge oscillators.

The conventional regenerative circuit consists of an electron discharge device to which are connected an output circuit, a tuned input or frequency-determining circuit and one or more circuits, or paths, for feeding energy from the output circuit to the resonant input circuit. Most applications of such circuits require the resonant frequency-determining circuit to be tunable over a range of frequencies and such tuning is usually accomplished by varying the capacitance of a variable condenser included in the frequency-determining circuit. One application, to which this invention is particularly applicable, is that of a beat frequency or local oscillator conventionally employed in a superheterodyne radio receiver wherein the frequency of the oscillator is varied simultaneously with the resonant frequencies of the signal-selector circuits by means of variable condensers mechanically connected to be adjusted by unicontrol means.

In modern receivers of the type mentioned it is often necessary to provide an oscillator which maintains its stability of operation over a frequency range extending from a lower limit of 550 kilocycles or less to an upper limit of 60 megacycles or more. Usually this is accomplished by dividing this wide frequency range into bands and employing different inductance elements in the tunable frequency-determining circuits for covering the several operating bands, switching means being provided for selectively connecting the inductances of different values in parallel with the tuning condensers of their respective tunable circuits.

In order to facilitate the control of such a system over the high-frequency portion of the extended frequency range, and for practical reasons of economy, it is desirable to use a single inductance in each of the tunable signal-selector circuits and the local oscillator frequency-determining circuit to determine the resonant frequencies of the several circuits over a wide ultra high-frequency band in the upper portion of the operating range. This range may include frequencies extending from a lower limit of 18 megacycles to an upper limit of 60 megacycles or more.

Certain problems arise in constructing an oscillator capable of stable operation over such a wide ultra high-frequency band. For example,

the higher operating frequencies require the use of an inductance in the frequency-determining circuit of the oscillator having a very low inductance value. Further, the extended frequency range requires the use of a variable condenser having a relatively large capacitance and a wide range of capacitance adjustment. These two factors combine to produce a low L/C ratio between the two elements of the frequency-determining circuit at certain frequencies within the band. This low L/C ratio makes it exceedingly difficult properly to load the oscillator tube when any of the conventional types of feed-back arrangement are employed. A further difficulty is encountered in securing a sufficiently tight coupling between the feed-back circuit and the frequency-determining circuit to insure a transfer of energy sufficient to maintain the oscillator in stable operation at all frequencies within the range. This difficulty arises from the fact that the leads between the inductance coil, the selector switch, and the tuning condenser have values of inductance which are appreciable compared to the total inductance in the tuned circuit, thus limiting the maximum attainable coefficient of coupling to a value substantially below the usual values attained in lower-frequency circuits.

It has been found that, if conventional feed-back arrangements be employed in applications of the type mentioned having a feed-back coupling inductance of sufficient size to insure the proper loading and proper degree of coupling, this feed-back circuit will have a natural frequency which approaches, and materially reduces the extent of, the operating frequency range of the oscillator.

It is an object of the present invention, therefore, to obviate the above difficulties by providing a feed-back arrangement, generally applicable to high-frequency regenerative circuits, which is substantially equally effective in its energy transfer function at all frequencies within a wide range of high frequencies.

It is a further object of this invention to provide a high-frequency electron discharge oscillator which includes a feed-back arrangement having the above operating characteristics, and which is capable of stable operation at all frequencies within an extended high-frequency range.

In accordance with this invention, the above objects are attained by providing a feed-back arrangement which includes a pair of paths each providing coupling between a different electrode of the electron discharge control device

and the frequency-determining circuit, and each being particularly effective to supply energy to this circuit over a portion of the operating frequency range, the two feed-back paths acting in aiding phase over the operating frequency range, that is, acting cumulatively to transfer energy to the frequency-determining circuit. In one embodiment of the invention, one of the feed-back paths is connected to the output electrode, or anode, of the electron discharge device and is primarily capacitively coupled to the tunable frequency-determining circuit. A second path is provided which is connected to one of the auxiliary electrodes as, for example, the suppressor grid of the device and is inductively coupled to the inductance element included in the frequency-determining circuit. In another embodiment of the invention, the two feed-back paths are each inductively coupled to the frequency-determining circuit, one of the paths being connected to the anode of the electron discharge device, and the second path being connected directly to the suppressor grid and, through a blocking condenser, to the screen grid.

25 The novel features which are believed to be characteristics of this invention are set forth with particularity in the appended claims. The invention itself, however, both as to its organization and the method of operation, together with further objects and advantages thereof, will best be understood by reference to the specification taken in connection with the accompanying drawings, in which Figs. 1 and 2 illustrate different embodiments of the invention; Fig. 3 illustrates the form of the invention shown in Fig. 2 as applied to a local oscillator of a superheterodyne broadcast receiver; and Fig. 4 illustrates certain operating characteristics of an oscillator embodying the present invention as compared 40 with the characteristics resulting from other feed-back arrangements.

Referring to Fig. 1 of the drawings, there is illustrated an embodiment of the invention in an electron discharge oscillator circuit. The circuit shown comprises an electron discharge device 1 having a cathode 2 preferably of the well-known unipotential type, an anode 3, a control grid 4, and screen and suppressor grids 5 and 6, respectively, all enclosed within an evacuated envelope 7 which is surrounded by a grounded metallic shield 8. Connected between the control grid 4 and ground, through a coupling condenser 9 and a booster winding 10, is a tunable frequency-determining circuit 11 which comprises 45 an inductance 12 shunted by a variable tuning condenser 13. The booster winding 10 is inductively coupled to the inductance 12 and functions to increase the impedance between the input electrodes thereby to improve the loading of 50 the oscillator tube. The cathode 2 is connected by the lead 14 to a tap 15 on the inductance 12 slightly above alternating ground potential. For the purpose of biasing the control grid 4 to the proper negative potential with respect to the 55 cathode 2, a resistor 16 is connected between this control grid and ground.

The anode or output circuit of the oscillator includes a source of anode potential 17 which is connected to the anode 3 and the auxiliary screen 70 electrode 5 through resistors 18 and 19, respectively. The series-connected source 17 and resistor 19 are shunted by a high-frequency bypass condenser 20.

In accordance with the present invention, stability of operation is procured over an extended

high-frequency range by providing two feed-back paths for supplying energy to the frequency-determining input circuit 11 and connected in the manner shown. One of these paths includes a circuit connected between the anode 3 and the high potential terminal of the circuit 11 and comprises a blocking condenser 21 connected in series with an inductance 22. The inductance 22 is designed to have a natural resonant frequency below the low-frequency end of the tuning range, by virtue of which this feed-back path is primarily effective over the lower-frequency portion of the tuning range. The second feed-back path comprises an inductance 25 having one terminal connected to the low potential terminal of the frequency-determining circuit 11 and the other terminal connected to the suppressor grid 6, the inductance 25 being tightly coupled to the inductance 12 of the frequency-determining circuit. The leakage inductance of this latter feed-back path is resonant with the tube capacitance and its distributed capacitance at a natural frequency above the upper limit of the operating band, by virtue of which it functions to transfer energy to the frequency-determining circuit 25 principally over the upper portion of the operating frequency range. It will, of course, be understood that the portions of the frequency band over which the two paths are respectively effective may be the reverse of that described. It 30 will be understood that, at the ultra high frequencies contemplated, any stray feed-back couplings, such as those due to interelectrode capacitances and distributed circuit capacitances, must be taken into consideration in proportion- 35 ing the main feed-back circuits.

With the feed-back paths arranged in the above described manner, and with the condenser 13 adjusted to tune the circuit 11 to a resonant frequency in the low-frequency portion of the range 40 approaching the lower limits of the frequency range, the feed-back voltage is impressed on the circuit 11 primarily through the path from the anode 3 to the high alternating potential terminal of the circuit 11. At these lower frequencies of 45 the range the second feed-back path, including the inductance 25, is of little effect. As the condenser 13 is adjusted to tune the circuit to frequencies above this low-frequency portion of the range, the second feed-back path comprising the 50 inductance 25 becomes increasingly effective until a frequency is reached, above which, and until the upper limit of the frequency range is reached, the transfer of energy to the circuit 11 is almost entirely through this second path. It will be understood that the energy supplied to the circuit 11 through the two feed-back paths is proportioned to maintain the oscillator voltage substantially constant over the frequency range. It will further be understood that the feed-back voltages 55 impressed on the circuit 11 by each of the two paths are in aiding phase relation over the operating frequency range and are proportioned so that a preselected uniform feedback with respect to frequency is obtained, whereby the oscillator voltage is maintained substantially constant throughout the frequency range.

By connecting the two feed-back paths to the different electrodes 3 and 6 interaction between the two paths is substantially eliminated, thereby 70 insuring maximum effectiveness of each path in its feed-back function. In this connection it will be seen that the feed-back arrangement represents a distinct improvement over the multi-feed-back path arrangements known to the art, and 75

- particularly the known arrangement wherein two feed-back paths are coupled in parallel between the oscillator tube anode, or another output electrode, and the frequency-determining circuit.
- 5 With the latter arrangement the interaction between the two feed-back paths considerably reduces the extent of the frequency range over which the oscillator is capable of stable operation.
- The embodiment of the invention illustrated in 10 Fig. 2 is similar to that of Fig. 1, except that each of the two feed-back paths is inductively coupled to the inductance 12 of the frequency-determining circuit. Thus, the path which is operative to supply energy to the frequency-determining circuit 15 over the lower portion of the operating frequency range comprises an inductance 26 connected between the low potential terminal of the circuit 11 and the anode 3 of the discharge device 1 through a blocking condenser 27, the coil 26 being 20 tightly coupled to the inductance 12. The second feed-back path, which is effective to supply energy to the frequency-determining circuit over the upper portion of the frequency range, is the same as the arrangement of Fig. 1 but is also effectively 25 connected to the auxiliary electrode 5 through the blocking condenser 28. With this circuit arrangement, wherein the second feed-back path is capacitively connected to the screen grid 5, the resistance 18 connected in the screen grid circuit 30 between the source 17 and the grid 5 effectively prevents high-frequency currents from flowing through the source 17 to ground and insures the passage of such currents through the feed-back path including the inductance 25.
- 35 The operation of the two feed-back paths in the system of Fig. 2 is, in general, the same as that described in connection with the feed-back arrangement of Fig. 1 but possesses certain advantages thereover. Thus, in order to tune the circuit of Fig. 1 to extremely high frequencies, it is necessary to raise the natural frequencies of either or both of the feed-back circuits including inductances 25 and 22, by reducing the inductances 25 or 22 or both; or to loosen their couplings to 40 the coil 12. Either expedient reduces the amount of energy feedback and thereby tends to produce instability in the operation of the oscillator at certain frequencies within the specified range. With the circuit of Fig. 2, on the other hand, the 45 natural frequency of the circuit including coil 25 may be raised to a sufficiently high value by decreasing the inductance of coil 25 to enable the circuit 11 to be tuned over the desired range, while still maintaining sufficient feedback to provide stable operation. The decrease in inductance 50 without a consequent decrease in energy feedback is possible because there is inherently less interaction between the feed-back paths of the circuit of Fig. 2 than between the two paths included in the arrangement of Fig. 1.
- A second practical advantage in the circuit of Fig. 2 over that of Fig. 1 has reference to the use of the oscillator as a beat frequency or local oscillator in a multi-band superheterodyne radio receiver. In such a receiver it is necessary selectively to interchange the inductances forming the inductive branch of the oscillator frequency-determining circuit as the receiver is adjusted to different signal carrier frequencies allocated in 55 the different bands. With the arrangement of Fig. 1 it is impractical to attempt to switch the inductance 18 out of the circuit when the inductance 12 is removed. Hence the inductance 18 remains in the oscillator circuit at all times; being 60 permanently connected between one electrode of

the tuning condenser 13 and the control electrode 4. The capacitance of this element to ground may have a deleterious effect on the frequency coverage of the other bands. In the circuit of Fig. 2, however, the coil 18 is omitted and such effects are avoided.

While it will be understood that the circuit specifications may vary according to the design of a particular application, the following specification of circuit constants for the oscillator circuit of Fig. 2 is included by way of example as being satisfactory when used in conjunction with an oscillator tube commercially known as the 6J7 tube.

Condenser 9	50	micro-microfarads	15
Condenser 27	700	micro-microfarads	10
Condenser 28	0.01	microfarad	5
Resistance 16	100,000	ohms	10
Resistance 18	15,000	ohms	20
Resistance 19	20,000	ohms	20

The inductances 12, 25 and 26 were supported on a single support with inductance 26 concentrically disposed within inductances 12 and 25, and with the inductances 12 and 25 forming a continuous winding, the specifications being as follows:

Inductance	Turns	Wire	Winding pitch	Diameter	30
25	114	No. 14	10 turns per inch	1 1/2	15
12	34	No. 14	10 turns per inch	1 1/2	15
26	12 1/2	No. 30	28 turns per inch	3/4	35

Certain refinements in the circuit arrangements shown in Figs. 1 and 2 tend to improve the operation to a considerable extent. One such refinement is that of connecting the cathode 2 to a point 18 on the inductance 12 slightly above the ground connection. Using the coil specifications given above this was accomplished by connecting the cathode to a point on the inductance 12 only a fraction of a turn removed from the ground terminal of the inductance. Another refinement particularly effective in improving the operation of the embodiment of the invention illustrated in Fig. 2 resides in the connection of the various circuit ground return leads to a single ground point 18'. When the oscillator shown is employed as a local oscillator in a superheterodyne receiver, this common point 18' should be that where the circuit lead from the rotor of the condenser 13 is connected to the chassis of the receiver.

Referring now to Fig. 3 of the drawings, there is illustrated the form of the improved oscillator shown in Fig. 2 as applied to a multi-band radio broadcast receiver of the well-known superheterodyne type. Briefly described, the receiver comprises a radio-frequency amplifier, indicated schematically at 38, connected to an antenna-ground circuit 31-32 and coupled by a multi-band coupling system generally indicated at 33 to the input electrodes 34 and 35 of a modulator tube 36. The radio-frequency selector and amplifier 38 may be of any conventional type and includes for each stage, a variable tuning condenser 37 and band-selecting switching means 38. The tube 36 is of the well-known heptode type connected as a pentode being provided with screen grids 39 and a second control grid 40 adjacent the cathode 35, to which is applied the output voltage from the local oscillator 4. Connected in cascade with the output circuit of the

modulator 36 are an intermediate-frequency amplifier 41, a detector and automatic amplification control source 42, an audio-frequency amplifier 43 and a sound reproducer 44. The automatic gain control bias potential may be applied to one or more of the stages of the radio-frequency selector and amplifier 30, modulator 36 and the intermediate-frequency amplifier 41, as desired, through the lead 45. The variable tuning condensers included in the several tunable circuits of the system are preferably ganged for unicontrol, as indicated by the dash lines 46. Similarly, the various band-selector switches are ganged for unicontrol adjustment, as indicated by the 15 dot and dash lines 47.

Considering first the operation of the receiver as a whole, without regard to the details of the oscillator, per se, the desired received signal wave is selected and amplified in the radio-frequency selector and amplifier 30, further selected and transferred by the coupling system 33 to the modulator 36 where the signal is converted into a modulated intermediate frequency. The signal, as thus converted, is amplified in the intermediate-frequency amplifier 41, rectified by the detector 42 thereby producing the audio-frequencies of modulation, which are amplified in the audio-frequency amplifier 43 and reproduced by the sound reproducer 44.

30 The amplification of the received signal is subject to automatic control by the automatic volume control bias potentials according to the manner well understood in the art.

The signal-selector circuits included in each of 35 the stages of the signal-selector and amplifier system 30 are exemplified by the coupling system indicated generally at 33. This system comprises coupling transformers 48, 49 and 50 each including a primary winding which may be selectively connected in the output circuit of the radio-frequency amplifier 30 by means of a band-selector switch 51, and a secondary winding which may be simultaneously and selectively connected to the input electrodes 34 and 35 of the modulator tube 36 by means of a band selector switch 40 52, by-pass condenser 53 and that of the modulator cathode biasing circuit 54. These three 45 transformers 48-50, inclusive, have progressively lower inductance values in the order named and are designed to be connected to operate over progressively higher-frequency bands covering 50 different portions of the extended frequency range over which the receiver is designed to operate. A single variable tuning condenser 55 is connected to the input circuit 34, 35 of the tube 36 55 selectively to vary the resonant frequency of the selector circuit 33 over the several frequency bands. Additional adjustably fixed aligning condensers 56, 57 and 58 are connected in shunt with the respective secondary windings of the 60 transformers 48, 49 and 50.

The local oscillator, which is identical in all 65 fundamental respects with that shown in Fig. 2 of the drawings, includes, in addition to the frequency-determining inductance 12, a pair of additional frequency-determining inductances 59 and 60 of progressively higher inductance. The inductances 12, 59 and 60 may be selectively connected, by a band-selector switch 63, in parallel 70 with the condenser 13 to control the frequency of the local oscillator. A second selector switch 64 is provided for selectively connecting the inductances 26, 61 and 62, which are coupled to the inductances 12, 59 and 60, respectively, to the 75 output circuit of the oscillator, thereby to pro-

vide the necessary energy feedback to the frequency-determining circuit. Auxiliary series-aligning condensers 65 and 66, associated with the circuits of inductances 59 and 60, respectively, and adjustably fixed trimmer condensers 67, 68 and 69, effectively connected in parallel with inductances 12, 59 and 60, respectively, are provided for maintaining a constant frequency difference between the resonant frequency of the signal selector and the local oscillator frequency. It will be understood that the unicontrol means 47, to which are mechanically connected the several band-selector switches 38, 51, 52, 63 and 64, may be actuated simultaneously to connect corresponding inductance coils, designed to operate over any one selected band of frequencies, in their respective associated circuits. Following such a band-selecting operation, the several tuning condensers may be adjusted by unicontrol means 46 to tune the selector circuits and the local oscillator circuit to make the receiver responsive to any desired signal-carrier wave frequency within the selected frequency band.

Although the receiver illustrated in Fig. 3 and described above is shown as comprising means whereby only three distinct frequency bands, covering different portions of the frequency spectrum, may be received, it will be understood that the number of bands may be increased by the addition of coupling channels in the several tunable signal-selector circuits and by a corresponding addition of coils having different inductance values in the tunable frequency-determining circuit of the local oscillator. However, it is desirable from the standpoint of cost of construction to minimize the number of such elements employed. If this is to be done without reducing the over-all range of carrier frequencies to which the receiver is responsive, it is necessary that one or more of the frequency bands be relatively wide. Expansion of the ultra high-frequency band to cover an extended frequency range of, for example, from 18 to 60 megacycles may be effected satisfactorily by employing the feed-back arrangement herein disclosed for use in the ultra high-frequency band, as shown in Fig. 3.

The improved operation resulting from coupling the two feed-back paths, in the previously described manner, is illustrated by the curves of Fig. 4, wherein the oscillator output in volts is plotted against frequency for a number of different oscillator circuit arrangements. In this figure the curve 72 represents the operating characteristic of the oscillator with the two feed-back paths inductively coupled, respectively, between the anode and frequency-determining circuit, and between the suppressor grid and screen grid and the frequency-determining circuit as was described in connection with the oscillator shown in Figs. 2 and 3. It will be seen that the oscillator output voltage remains high and substantially constant over the entire operating frequency range extending between 20 megacycles and 65 megacycles. The remaining curves illustrate the resulting operation when one or two feed-back paths are coupled between the frequency-determining circuit and the oscillator anode alone. The curve 73 shows the corresponding characteristic when the high- and low-frequency energy transfer paths are both loosely inductively coupled to the inductance of the frequency-determining circuit and are both connected to the anode of the oscillator tube. The curve obtained when only the low-frequency path is used is shown at 74, and the curve obtained 75

when only the high-frequency path is used is shown at 72''. It will be seen that with any one of the three last-named arrangements the oscillator stops operating over a substantial portion of the frequency band. The curve 74 illustrates the results obtained with the two feed-back paths connected to the anode and inductively coupled to the inductance of the frequency determining circuit, the low-frequency feed-back path being 5 tightly coupled, and the high-frequency path being loosely coupled to the inductance of the frequency-determining circuit. With this arrangement the limited range of adjustment of the frequency-determining circuit of the oscillator would not permit the circuit to be tuned to a frequency below approximately 25 megacycles. The curve 78 is for a feed-back arrangement similar to that from which curve 74 was obtained with the order of coupling reversed, namely, the 10 high-frequency path was tightly coupled and the low-frequency path was loosely coupled to the inductance of the frequency-determining circuit. With this arrangement the limited range of adjustment of the frequency-determining circuit 15 would not permit the circuit to be tuned to a frequency above 40 megacycles. The characteristic curve 71 is for a similar arrangement wherein the high-frequency path was moderately tightly coupled, and the low-frequency path was tightly coupled to the inductance forming one branch of the frequency-determining circuit. With this type of coupling the limited range of adjustment of the frequency-determining circuit prevented the circuit from being tuned to a frequency below 20 25 megacycles or to a frequency above 60 megacycles.

While there are described herein what are at present considered to be the preferred embodiments of the invention, it will be understood that 30 various changes and modifications may be made therein without departing from the invention, and it is contemplated in the appended claims to cover all such changes and modifications as fall within the true spirit and scope of the invention.

45 What is claimed is:

1. An oscillator comprising, an electron discharge device including an input electrode, a cathode and a plurality of additional electrodes, a resonant circuit having a series inductance 50 value of less than 1 microhenry connected to said input electrode and tunable over a wide range of high frequencies, and a plurality of feed-back paths, each of said paths being coupled between a different one of said additional electrodes and said circuit, said feed-back paths being connected in aiding phase relation and having reactive constants so proportioned that said paths are individually effective primarily only over different complementary portions of said frequency range, 55 whereby said oscillator is maintained in stable oscillation over said range.

2. An oscillator comprising, an electron discharge device including a cathode, an anode, an input electrode, and a plurality of additional electrodes one of which is an output electrode, a resonant circuit having a series inductance value of less than 1 microhenry connected to said input electrode and tunable over a wide range of high frequencies, a feed-back path coupled between 60 said output electrode and said circuit and having reactive constants so proportioned that said path is effective to supply energy to said circuit primarily over a portion of said frequency range including one limiting frequency, and a second 65 feed-back path coupled between at least one

of said additional electrodes and said circuit and connected in aiding phase relation with said first feed-back circuit and having reactive constants so proportioned that said second path is effective to supply energy to said circuit primarily over a portion of said frequency range including the other frequency limit, said feed-back paths being so proportioned and arranged that said oscillator is maintained in stable operation over 70 said range.

3. An oscillator comprising, an electron discharge device including an input electrode, a cathode, and a plurality of additional electrodes, a resonant circuit having a series inductance value of less than 1 microhenry connected to said input electrode and tunable over a wide range of high frequencies, and a plurality of feed-back paths 15 for supplying energy to said resonant circuit, each of said paths being coupled between a different one of said additional electrodes and said circuit 20 and the impedance of each of said paths being so proportioned with respect to the impedance of the other of said paths that the energy supplied to said circuit through said paths maintains the oscillator voltage substantially constant over said 25 frequency range.

4. An oscillator comprising, an electron discharge device including a cathode, an anode, a control grid and an auxiliary grid, a resonant circuit connected between said control grid and cathode and including an inductance element and a condenser effectively connected in parallel, said circuit being tunable over a range of frequencies, a feed-back circuit connected to said anode and including an inductance element coupled to said first-named inductance element, the reactive constants of said feed-back circuit being so proportioned that said feed-back circuit is effective to supply energy to said resonant circuit primarily over the lower portion of said frequency range, and a second feed-back circuit connected to said auxiliary grid and including an inductance element coupled to said first-named inductance element, the reactive constants of said second circuit being so proportioned that said 30 last-named circuit is effective to supply energy to said resonant circuit primarily over the remaining portion of said frequency range, said inductance elements included in said feed-back circuits and the couplings between said inductance elements and said first-named inductance element being so proportioned that the oscillator 35 is maintained in stable oscillation at all frequencies within said range.

5. An oscillator comprising, an electron discharge device including a cathode, an anode, a control grid and a pair of additional grids, a resonant circuit connected between said control grid and cathode including an inductance element and a condenser effectively connected in parallel, said circuit being tunable over a range of frequencies, a feed-back circuit coupled between said anode and said resonant circuit, the reactive constants of said feed-back circuit being so proportioned that said feed-back circuit is effective to supply energy to said resonant circuit primarily over the lower portion of said frequency range, a second feed-back circuit connected to one of said additional grids and including an inductance element coupled to said 60 last-named inductance element, and a condenser for coupling said last-named feed-back circuit to the other additional grid, the reactive constants of said second circuit being so proportioned that said last-named feed-back circuit is ef- 65 70 75

fective to supply energy to said resonant circuit primarily over the remaining portion of said frequency range.

6. An oscillator comprising, an electron discharge device including a cathode, an anode, a control grid, a screen grid and an additional grid, a resonant circuit connected between said control grid and cathode including an inductance element and a condenser effectively connected in parallel, said circuit being tunable over a range of frequencies, a screen grid circuit including a source of potential, a feed-back circuit coupled between said anode and said resonant circuit, the reactive constants of said feed-back circuit being so proportioned that said feed-back circuit is effective to supply energy to said resonant circuit primarily over a portion of said frequency range including one limiting frequency, a second feed-back circuit connected to said additional grid including an inductance element coupled to said last-named inductance element, a condenser for coupling said second feed-back circuit to said screen grid, the reactive constants of said second circuit being so proportioned that said second feed-back circuit is effective to supply energy to said resonant circuit primarily over a portion of said frequency range, and means connected in said screen grid circuit for preventing high-frequency currents from flowing through said source of potential.

7. An oscillator comprising, an electron discharge device including a cathode, an anode, a control grid and a pair of additional grids, a resonant circuit connected between said control grid and cathode and including an inductance element and a condenser effectively connected in parallel, said circuit being tunable over a range of frequencies, a feed-back circuit connected to said anode and including an inductance element coupled to said first-named inductance element, the reactive constants of said feed-back circuit being so proportioned that said feed-back circuit is effective to supply energy to said resonant circuit primarily over the lower portion of said frequency range including the lower limiting frequency, a second feed-back circuit connected to one of said additional grids and including an inductance element coupled to said first-named inductance element, and a condenser for coupling said second feed-back circuit to said other additional grid, the reactive constants of said second circuit being so proportioned that said second feed-back circuit is effective to supply energy to said resonant circuit primarily over the remaining portion of said frequency range.

8. An oscillator comprising, an electron discharge device including a cathode, an anode, a control grid and a pair of additional grids, a resonant circuit connected between said control grid and ground and including an inductance element and a condenser effectively connected in parallel, said circuit being tunable over a range of frequencies, a connection between said cathode and a point on said inductance element slightly above the ground connection, a feed-back circuit connected to said anode and including an inductance element coupled to said first-named inductance element, the reactive constants of said feed-back circuit being so proportioned that said feed-back circuit is effective to supply energy to said resonant circuit primarily over the lower portion of said frequency range, a second feed-back circuit connected to one of said additional grids and including an inductance element coupled to said first-named inductance element, and a condenser for coupling said second feed-back circuit to said other additional grid, the reactive constants of said second circuit being so proportioned that said second feed-back circuit is effective to supply energy to said resonant circuit primarily over the remaining portion of said frequency range.

9. In combination, an electron discharge device including an input electrode, an output electrode and a pair of additional electrodes, a resonant circuit connected to said input electrode and tunable over a range of frequencies, and feed-back means for supplying energy to said resonant circuit, said means including a pair of paths coupled respectively between said output electrode and said circuit and between said pair of additional electrodes and said circuit, said feed-back paths being connected in aiding phase relation and having reactive constants so proportioned that said paths are individually effective primarily over different complementary portions of said frequency range and provide a preselected and substantially uniform feedback of energy throughout said frequency range.

10. In combination, an electron discharge device including an input electrode, an output electrode and a pair of additional electrodes, a resonant circuit connected to said input electrode and tunable over a range of frequencies, a feed-back path coupled between said output electrode and said circuit and having reactive constants so proportioned that said path is effective to supply energy to said circuit primarily over a portion of said frequency range including one limiting frequency, and a second feed-back path coupled between said pair of additional electrodes and said circuit and having reactive constants so proportioned that said second path is effective to supply energy to said circuit primarily over another portion of said frequency range including the other limiting frequency, said feed-back paths being connected in aiding phase relation and being so proportioned that they provide a preselected and substantially uniform feed-back of energy throughout the frequency range.

11. In combination, an electron discharge device including a cathode, an anode, a control grid, and an auxiliary grid, a resonant circuit comprising an inductance element and a condenser effectively connected in parallel, said circuit being connected between said control grid and ground, a connection between said cathode and a point on said inductance element slightly above the ground connection, a feed-back circuit connected between said anode and ground and including an inductance element tightly coupled to said first-named inductance element, and a second feed-back circuit connected between said auxiliary grid and ground and including an inductance element tightly coupled to said first-named inductance element, said ground connections terminating at a common point.

12. In combination, an electron discharge device including a cathode, an anode, a control grid, a screen grid, and an auxiliary grid, a resonant circuit comprising an inductance element and a condenser effectively connected in parallel, said circuit being connected between said control grid and ground, a connection between said cathode and a point on said inductance element slightly above the ground connection, a feed-back circuit connected between said anode and ground including an inductance element tightly coupled to said first-named inductance element, and a second feed-back circuit connected between said auxiliary grid and ground and including an inductance element tightly coupled to said first-named inductance element.

said auxiliary grid and ground including an inductance element tightly coupled to said first-named inductance element, and a condenser connected between said auxiliary grid and said screen grid, said ground connections terminating at a common point.

13. An oscillator comprising an electron discharge device including an input electrode, a cathode and a plurality of additional electrodes, a resonant circuit having a series inductance value of less than 1 microhenry connected to said input electrode and tunable over a wide range of ultra-high frequencies, and a plurality of feed-back paths, each of said paths being coupled between a different one of said additional electrodes and said circuit, said feed-back paths being connected in aiding phase relation and having reactive constants so proportioned and arranged that they are individually effective primarily over different complementary portions of said frequency range,

whereby said oscillator is maintained in stable oscillation over said range.

14. An oscillator comprising an electron discharge device including an input electrode, a cathode and a plurality of additional electrodes, a resonant circuit having a series inductance value of less than 1 microhenry connected to said input electrode and tunable over a wide range of frequencies including the range from approximately 18 megacycles to approximately 60 megacycles, and a plurality of feed-back paths, each of said paths being coupled between a different one of said additional electrodes and said circuit, said feed-back paths being connected in aiding phase relation and having reactive constants so proportioned that they are individually effective primarily over different complementary portions of said frequency range, whereby said oscillator is maintained in stable oscillation over said range.
